UNITED STATES PATENT OFFICE.

NELSON M. BAKER, OF SOUTHERBRIDGE, MASSACHUSETTS.

GOOGLES.

1,078,405.

Specification of Letters Patent.

Patented Nov. 11, 1913.

Application filed March 17, 1913. Serial No. 754,705.

To all whom it may concern:

Be it known that I, NELSON M. BAKER, a citizen of the United States, residing at Southbridge, in the county of Worcester and 5 State of Massachusetts, have invented certain new and useful Improvements in Goggles, of which the following is a specification.

My invention relates to goggles and has 10 particular reference to that type of goggles which may be folded to facilitate carrying.

The leading object of my invention is to produce an improved construction of folding goggles.

15 My further object is to so construct a pair of goggles that when they are folded the guards are satisfactorily protected.

With these and other objects in view my invention consists of the construction and 20 arrangement of parts fully described and claimed in the annexed specification and claims and shown in the accompanying drawings, it being understood that I may make slight modifications therein without 25 departing from or exceeding the spirit of my invention, provided said modifications fall within the scope of the appended claims.

Figure I shows a fragmentary front view of my improved folding goggle in open position. Fig. I^a is a similar view of another form. Fig. II is a top plan view of Fig. I. Fig. II^a is a similar view of Fig. I^a. Fig. III is a front elevation of my improved goggle in folded position. Fig. IV is a top plan view thereof. Fig. V is an enlarged fragmentary perspective view. Fig. VI is a partial elevation showing a modified bridge and guard. Fig. VII is a partial elevation showing a modified construction of guard. 40 Fig. VIII is a partial elevation showing the bridge attached above the arm carrying the guard and also showing a slightly modified form of guard.

Referring to the drawings by reference numerals, in which similar characters denote corresponding parts throughout the several views, the usual lenses are designated by the numeral 1. The lenses may be secured in any desired manner, and in Fig. I, 45 I have shown them fastened in the eye wire 2, provided with the end pieces 3 on the outer end thereof. However, I may use a frameless construction as shown in Fig. I^a, the lenses being held in place by the end 50 clips 4. The temples 5 are fastened thereon

in the ordinary manner, but in place of the temples a head band, 6 such as shown in Fig. I^a, may be used.

Fastened to the frame of the lens is the arm 7; this arm has a flattened horizontal portion 8 which forms a pivot seat for the bridge 9, the bridge being pivoted to each lens at its extremities. The arm 8 is formed with a loop therein and a guard is rigidly fastened to the end thereof. While 65 I have shown my guard as oval shaped in most of the views, it will be understood that I do not limit myself thereto as any type of guard may be used advantageously in my construction.

70 The advantages of my invention will be best understood by referring to Fig. IV of the drawings which shows the goggles in a folded position and shows the guards immediately under the bridge and in the same 75 vertical plane therewith. It is apparent, therefore, that the guards will be satisfactorily protected from both crushing and breaking off. The looped arm connecting the guards to the lens frames allows for adjustment of the guards, and in Fig. VIII, I have shown the arm fastened to the rear of the guard. This allows a free front edge and allows the guard to be adjusted to engage the nose.

80 In Fig. V, I have shown an offset 11 on the arm 7 which engages the bridge when the goggles are folded and keeps one lens from being folded to a greater angle than the other. This brings the guards into 85 desired position for their protection, as shown in Fig. IV.

85 In Fig. VI, I have shown a saddle bridge and I have slightly altered the construction of the guard arm for particular use 90 with this bridge, whereby the arm will bend around the loop 12 and bring the guard under the bridge, the object being substantially the same as in my other construction.

95 In Fig. VII, I have shown the end of the 100 arm which fastens to the guard as bifurcated and attached to the guard above and below the center thereof.

105 In Fig. VIII, I have shown a bridge fastened above the horizontal portion of the arm instead of below and I have used an ordinary spectacle guard 10' in connection therewith, it being understood that I do not limit myself to the forms of guard as I have shown here.

Having thus fully described my invention, what I claim as new and desire to secure by Letters Patent is:

1. A folding goggle comprising lenses, an arm attached to each lens, a flattened horizontal portion in the arm forming a pivot seat, a bridge pivoted to the arm, a curved portion in the arm exterior of the pivot seat and a guard on the end of the curved portion, the guard being adapted to fold under the bridge.
2. A folding goggle comprising lenses, an arm attached to each lens, a flattened portion in the arm forming a pivot seat, a bridge pivoted to the arm, an elongated curved portion in the arm, said portion extending outwardly, then rearwardly and downwardly and then inwardly therefrom, and a guard fastened on the end thereof.
3. In a folding goggle in combination with a pair of lenses, a bridge pivoted thereto, a guard rigidly connected to each of the lenses and adapted to fold immediately under and in the same vertical plane with the bridge.
4. A folding goggle comprising lenses, a bridge, frames for the lenses pivoted to the bridge,

bridge and a guard rigidly fastened to each frame and adapted to fit under the bridge when the goggles are folded.

30

5. In a folding goggle, a pair of lenses, a rigid bridge pivoted thereto, an arm connected to each of the lenses, said arm having a pivot seat therein for the bridge, a curved elongated portion extending from the arm and carrying a guard on the end thereof, said guard being so placed that it folds immediately under and in the same vertical plane with the bridge.

35

6. A folding goggle comprising a pair of lenses, a bridge pivoted thereto, a pair of arms fastened to the lenses, a guard on the end of each arm and an offset in the arm to engage the bridge and limit the folding of the goggles so that the guard folds immediately under and in the same vertical plane with the bridge.

40

In testimony whereof I affix my signature in presence of two witnesses.

NELSON M. BAKER.
